UNITED STATES PATENT OFFICE.

JOHN HOPE, JR., OF PROVIDENCE, RHODE ISLAND, ASSIGNOR OF ONE-HALF
TO WILLIAM V. DABOLL, OF SAME PLACE.

AUTOMATIC SWITCH FOR STREET-RAILWAYS.

SPECIFICATION forming part of Letters Patent No. 351,440, dated October 26, 1886.

Application filed March 25, 1886. Serial No. 196,519. (No model.)

To all whom it may concern:

Be it known that I, JOHN HOPE, Jr., a citizen of the United States, and a resident in the city and county of Providence, State of Rhode Island, have invented an Improvement in Automatic Switches for Street-Railways, of which the following description, in connection with the accompanying drawings, is a specification, like letters on the drawings representing like parts.

Heretofore in automatic switches for street-railway service the switch-tongue has been operated by driving one of the animals hitched to the car onto one of a pair of movable tables or platforms set in the road-bed, at either side of one of the rails of the track, so that the weight of the animal caused the table to be depressed, which in turn actuated the switch-tongue to open or close the switch, as desired, so as to cause the car to pass onto a side or branch track, or to continue its way on the main track.

In this my improved automatic switch for street-railway service the switch-tongue is operated to open or close the switch, and enable the car to be switched from the main to the side track, or to continue its way on the main track, by a wheel or wheels of the car itself, and not by an animal hitched thereto, the flange of one of the forward wheels of the car being caused to bear against a slide having a projection or boss arranged in the line of travel of the flange of the car-wheel in such manner that in the onward travel of the wheel the projection or boss on the slide is forced to one side, thus giving the slide an endwise movement, which actuates a lever connected with said slide and with the pivoted switch-tongue, and fulcrumed intermediate of the two to operate in turn the switch-tongue, and thus open or close the switch.

To this end my invention consists, primarily, of the combination, with a pivoted switch-tongue placed at the junction of a main and side track, of a slide having a boss or projection arranged transversely in the line of that rail to which the switch-tongue is pivoted, and adapted to be moved outwardly from said rail by the flange of that wheel of a car approaching the switch which is nearest said switch-tongue, and a lever connected with the switch-

tongue and adapted to be operated by the slide, substantially as hereinafter particularly described, and pointed out in the claims.

Figure 1 shows in plan view my invention 55 as applied to a street-railway; Fig. 2, a detail in side elevation, to be referred to.

The main track with the rails a a' , the side track with its rails b b' , and the pivoted switch-tongue c , at the junction of the rails a b , are 60 and may be of usual or preferred construction. In connection with the switch-tongue I provide a slide and an intermediate lever pivoted or fulcrumed between the slide and switch-tongue, and held in engagement with said slide 65 and tongue. The slide is herein shown as a bar, D , arranged across the main track forward of the switch-tongue c , the rails a a' thereof being cut away, as at x , or with their ends set apart from each other, to permit the 70 projecting or enlarged portions d of the slide-bar D to freely move in a plane at right angles to said rails in such manner that the upper surface or face of the projections d are preferably flush or even with the tread a^2 of 75 the rails a a' . These projections are provided at their inner or opposite ends with rounded faces or bosses d' d'' , which are set at a sufficient distance from each other to enable one or the other of them to project inwardly from 80 the tread a^2 of either rail a or a' , so as to stand in the path of movement of the flange e or f of either of the front car-wheels, E F . In the present instance the slide-bar D is provided at or about its center with a notch to receive 85 the tapered end g of the lever G , which is fulcrumed or pivoted to the base h , in this instance by a pin, g' , and whose other end extends beneath the switch-tongue c , and is pivoted or attached thereto by the pin c' .

I have shown the slide-bar and lever as enclosed in a box, H , of which the base h forms the bottom, the said box protecting the parts from damage and from becoming clogged or obstructed.

In Fig. 1 the parts are shown in normal position, with the switch closed, the switch-tongue c resting against the rail a' of the main track. With the parts in such position a car may be switched onto the side or branch track 100 by driving the animal or animals hitched thereto in the direction or angle of the side track,

as shown by the arrow 2, before reaching said side track, as in the case wherein the well-known automatic switch having movable platforms or tables is employed, so as to cause the 5 flange *f* of the wheel *F* (representing the like wheel on a street-car) to strike and push aside the boss *d*' out of its path, and thus give end- 10 wise movement to the slide-bar, to actuate the lever, and in turn operate the switch-tongue 15 to open the switch, when the parts will assume the position shown in dotted lines, Fig. 1. After a car has passed onto the side or branch track, and it is desired that the next car following shall pass the switch and continue on 20 the main track, all that is necessary to be done is to drive the animal or animals of such succeeding car in a direction opposite to that indicated by the arrow 2, when the flange *e* of the wheel *E* will strike the boss *d*', which is 25 at the time in the path of movement of said flange, when the boss will be moved to one side to actuate the slide-bar, lever, and tongue to close the switch.

The slide-bar is actuated only when one of 25 its bosses is struck or pressed against with considerable force by the flange of one of the car-wheels, and for this reason, in connection with the fact that the rails are sufficiently far apart to permit slight lateral play of a pair of 30 wheels between them, it is not absolutely essential, when the switch is closed, to drive the car animal or animals off to one side of the track to insure the car passing the switch and continuing on the main track, since the car may 35 continue its straight course along the main track without operating the slide-bar to such a degree as to open the switch.

In Fig. 2 the forward wheels of a car are

shown in the switch, while the rear wheels are, in this instance, in the line of the slide-bar, so that any possible side or lateral play of the rear wheels tending to press against the boss to close the switch, such closure would be prevented by the forward wheels being at the time in the switch. 40

What I claim is—

1. The combination, substantially as described, with a pivoted switch-tongue, of a slide having a boss or projection arranged transversely in the line of that rail to which the switch-tongue is pivoted, and adapted to be moved outwardly from said rail by the flange of that wheel of a car approaching the switch which is nearest said switch-tongue, and a lever connected with the switch-tongue 55 and adapted to be operated by the slide, for the purpose set forth.

2. The combination, substantially as described, with a pivoted switch-tongue located at the junction of a main and a side track, as 60 specified, of a slide-bar arranged across the main track and having a projection or boss at each end, one or the other of which normally projects inwardly from the tread of the contiguous rail, as specified, and a pivoted 65 lever connected with the switch-tongue and adapted to be operated by the slide-bar, for the purpose specified.

In testimony whereof I have signed my name to this specification in the presence of two 70 subscribing witnesses.

JOHN HOPE, JR.
